HAIR CURLER

Martha M. Talbot, Detroit, Mich.

Application March 18, 1946, Serial No. 655,163

4 Claims. (Cl. 132—40)

1

This invention relates to hair curlers and in particular to hair curlers which may be used to make finger curls as well as pin curls.

In the prior art many types of hair curlers have been employed upon which hair is curled and held in curled relationship for a period of time, usually during the night, to accomplish the setting of the curl.

The prime object of the present invention is to provide a more effective and more desirable hair curler which will hold hair curled firmly thereon during the period of time required to set the curl, which allows for ventilation and drying of the hair being curled during the setting of the curl, which will accomplish a curl that will have more lasting qualities than normally possible to obtain with overnight setting, and which is comfortable during use.

Other objects of the invention will become apparent by reference to the following detailed description taken in connection with the accompanying drawing, in which:

Fig. 1 is a longitudinal elevational view of a long slender sheathed hair curler embodying the invention of proportions normally employed in accomplishing "finger curls," the sheath thereof is shown turned back and portions thereof are shown in section to illustrate the construction more clearly.

Fig. 2 is an elevational view similar to Fig. 1 except that a tuft of hair is anchored in the end of the curler stem and is wrapped spirally therearound.

Fig. 3 is an end elevational view taken on the line 3—3 of Fig. 2.

Fig. 4 is a longitudinal elevational view similar to Fig. 2 showing the curler disclosed in Fig. 1 in its curl set position with its sheath drawn over hair wrapped in spiral curled relationship around the stem thereof.

Fig. 5 is a longitudinal elevational view of a short bulbous sheathed hair curler embodying the invention of proportions normally employed in accomplishing "pin curls," the sheath thereof is shown turned back and portions thereof are shown in section to illustrate the construction more clearly.

Fig. 6 is an elevational view similar to Fig. 5 except that a tuft of hair is anchored in the end of the curler stem and is wrapped circumferentially therearound.

Fig. 7 is an end elevational view taken on the line 7—7 of Fig. 6.

Fig. 8 is a longitudinal elevational view similar to Fig. 6 showing the curler disclosed in Fig. 5

in its curl set position with its sheath drawn over hair wrapped around the stem thereof.

Referring now to the drawing wherein like numerals refer to like and corresponding parts throughout the several views, the illustrative embodiment of the invention disclosed in Figs. 1-4 inclusive is preferably employed to accomplish finger curls and comprises a relatively long hollow stem 10 of soft pliable rubber preferably having a plurality of closely spaced staggered ventilation apertures 11 therethrough and an anchorage slot 12 formed at one end thereof. The other end of the said hollow stem 10 is preferably tapered as indicated by the numeral 13 and has an annular anchorage groove 14 formed therearound. A thin expansible rubber sheath 15 preferably annularly beaded at both ends and having a plurality of closely spaced ventilation apertures 16 therethrough is secured by rubber cement or other suitable heat and moisture resistant cementitious material at its small annularly beaded end 17 into the annular anchorage groove 14 of the stem 10. The said expansible sheath 15 is annularly beaded at its free end 18 to avoid tearing of the said sheath 15 when it is expanded and drawn over hair wrapped onto the said stem 10 and to provide strength to avoid tearing of the sheath 15 when it is drawn from its curl set position indicated in Fig. 4.

In using the hair curler disclosed in Figs. 1-4 inclusive to accomplish a finger curl, a tuft of hair 19 is placed through the anchorage slot 12 in the stem 10 as indicated in Fig. 2 and is wrapped spirally around the said stem 10 of the hair curler whereupon the sheath 15 is drawn over the hair wrapped on the stem 10 as indicated in Fig. 4. The curl may be started any desired distance from the scalp indicated by the dot and dash line 20 in Figs. 2 and 4. After the curl sets, preferably overnight, the sheath 15 is drawn back to the position indicated in Fig. 2 and the curl is released by disengaging the tuft of hair 19 from the anchorage slot 12.

Referring now to the embodiment of the invention shown in Figs. 5-8 inclusive, the hair curler disclosed is preferably employed to accomplish pin curls and comprises a short hollow stem 30 of soft pliable rubber preferably having a plurality of closely spaced staggered ventilation apertures 31 therethrough and an anchorage slot 32 formed in one end thereof. The other end of the said hollow stem 30 is preferably tapered as indicated by the numeral 33 and has an annular anchorage groove 34 formed therearound. A thin expansible rubber sheath 35 preferably an-

nularly beaded at both ends and having a plurality of closely spaced ventilation apertures 36 therethrough is secured by rubber cement or suitable heat and moisture resistant cementitious material at one annular beaded end 37 into the annular anchorage groove 34 of the stem 30. The said expansible sheath 35 is annularly beaded at its free end 38 to avoid tearing of the said sheath 35 when it is expanded and drawn over hair wrapped onto the said stem 30 and to provide strength to avoid tearing of the sheath 35 when it is drawn from its curl set position indicated in Fig. 8. It will be noted that the said expansible sheath 35 is bulbous in form to accommodate it to being drawn over hair wound in circumferential overlapped relationship around the said stem 30.

In using the hair curler disclosed in Figs. 5-8 inclusive to accomplish a pin curl, a tuft of hair 39 is placed through the anchorage slot 32 in the stem 30 and is wrapped in circumferential overlapped relationship around the said stem 30 of the hair curler whereupon the sheath 35 is drawn over the hair wrapped on the stem 30 as indicated in Fig. 8. The curl may be started at any desired distance from the scalp indicated by the dot and dash line 49 in Figs. 6 and 8. After the curl sets, preferably overnight, the sheath 35 is drawn back to the position indicated in Fig. 6 and the curl is released by disengaging the tuft of hair 39 from the anchorage slot 32.

Although but two embodiments of the invention have been disclosed and described in detail, it is obvious that many changes may be made in the size, shape, arrangement and details of the various elements of the invention without departing from the spirit and scope thereof as defined by the appended claims.

I claim:

1. A hair curler comprising a stem around which hair to be curled is wound having a hair anchorage slot adapted to receive a tuft of hair formed near one end thereof, and an expansible

sheath secured at one end to the other end of the said stem adapted to be drawn over hair wound on said stem.

2. A hair curler comprising a hollow stem of resilient material having a plurality of radially disposed apertures therethrough, the said hollow stem having an anchorage slot adapted to receive a tuft of hair formed near one end thereof, and an expansible tubular sheath having a plurality of radially disposed apertures therethrough secured at one end to the other end of the said stem adapted to be drawn over hair wound on said stem.

3. A hair curler comprising a stem around which hair to be curled is wound having a hair anchorage slot adapted to receive a tuft of hair formed near one end thereof, and an expansible sheath having annularly beaded ends secured at one annularly beaded end to the other end of the said stem adapted to be drawn over hair wound on said stem.

4. A hair curler comprising a hollow stem having a plurality of radially disposed apertures therethrough, the said hollow stem having an anchorage slot adapted to receive a tuft of hair formed near one end thereof, and an expansible tubular sheath having annularly beaded ends and a plurality of radially disposed apertures therethrough secured at one annularly beaded end to the other end of the said stem adapted to be drawn over hair wound on said stem.

MARTHA M. TALBOT.
